UNITED STATES PATENT OFFICE.

JOHN T. WALSH, OF OTTAWA, ILLINOIS.

WHIPPING DEVICE.

1,139,606.

Specification of Letters Patent. Patented May 18, 1915.

Application filed August 31, 1914. Serial No. 859,462.

To all whom it may concern:

Be it known that I, JOHN T. WALSH, a citizen of the United States, residing at Ottawa, in the county of La Salle and State of Illinois, have invented certain new and useful Improvements in Whipping Devices; and I do declare the following to be a full, clear, and exact description of the invention, such as will enable others skilled in the art to which it appertains to make and use the same.

This invention relates to new and useful improvements in whip supports and manipulating means therefor, and more particularly to a device of this character applicable to a binder and the primary object of the invention is to provide a device of this character which will enable the usual buggy whip to be used in connection with a binder to urge onward the particular animal which is lagging.

A further object of the invention resides in providing a device which may be quickly and readily operated from the seat of the binder which is understood to be considerable distance from the draft attaching means.

A still further object resides in providing a device which is simple and durable in construction, inexpensive to manufacture and one which will be very efficient and useful in operation.

With these and other objects in view my invention consists of the novel features of construction, combination and arrangement of parts as will be hereinafter referred to and more particularly pointed out in the specification and claims.

In the accompanying drawings forming a part of this application: Figure 1 is a side elevation of a device constructed in accordance with my invention and applied to a portion of a binder; Fig. 2 is a plan view thereof with parts in section; Fig. 3 is a similar view showing the device in operative position; Fig. 4 is a vertical section as seen on line 4—4 of Fig. 1, looking in the direction of the arrow; and, Fig. 5 is a horizontal section as seen on line 5—5 of Fig. 1 looking in the direction of the arrows.

In describing the invention I shall refer to the drawing in which similar reference characters designate corresponding parts throughout the several views and in which 1 designates the tongue of a binder of the usual or any preferred type. Connected to the lower supporting frame 2 and mounted on this frame 2 through the medium of supports 3 or any other desired means is a foot board 4. This foot board as usual, supports the various levers, the bundle carrier and the seat and particularly supports what is known to the art as the tilting lever indicated at 5. My invention while involving a support and operating means for a whip has connection with this tilting lever as will be hereinafter and more particularly set forth.

The outer end of the tongue 1 has an arm or the like 6 secured thereto which extends laterally of said tongue and supports the double trees 7. Mounted on the double trees is a casting 8 the central portion of which is somewhat raised above said double trees and designed to provide a bearing 9 in which is rotatably supported the lower end of a rod 10. This rod is removably mounted in place in the bearing and carries a segmental pulley wheel 11 to rest on the upper end of the bearing 9. This segmental pulley wheel is adjustably and removably secured in place by means of a set screw 12 and the purpose thereof will be hereinafter and more particularly set forth. The portion of the rod 10 above the segmental pulley 11 is distorted as shown at 13 and the extreme upper end thereof is bent as at 14. An elongated bracket or the like is fulcrumed intermediate of its ends on the upper bent end 14 of said rod 10 and is designed to form a lever 15 the greater portion of which projects forwardly of the device and is bent somewhat downwardly. The portion of the casting forming this lever 15 in the forward portion thereof is designed to form an adjustable clamp 16 which forms the whip socket proper.

From the above description it will be seen that the whip socket is supported some distance above the double trees, and in view

of the particular construction supporting the rod 10 it will be appreciated that said whip socket may be directed toward one side or the other of the binder, according to 5 the animal found to be lagging. In order to provide means for operating the rod so as to dispose the whip socket in one direction or the other a pair of flexible connections such as cables or the like 17 are provided, the ends of which are connected to 10 the opposite portions of the segmental pulley 11 and guided through the grooves therein. These flexible connections extend rearwardly and are guided through a double pulley 18 which is supported on a block or 15 the like 19 carried on the tongue 1 just forward of the lower supporting frame 2. The connections 17 are then guided through a loop or guide 20 which is carried on the forward end of the foot board 4 and extend upwardly therefrom. The free ends of said 20 connections are engaged with an actuating lever 21 which is fulcrumed intermediate of its ends on the tilting lever 5 hereinbefore referred to. The ends of the connections are 25 engaged with the lever on opposite sides of the fulcrum point thereof so that when said lever is actuated in one direction the segmental pulley will be tilted in a position to direct the whip socket toward one side of the binder and when operated in the other direction a reverse position will be taken by the whip socket. This lever is disposed adjacent the driver's seat so that the same may 30 be readily actuated at the will of the driver. In order to take up any slack in the connections 17 the coil springs 22 are provided in the length thereof.

The construction above described sets 40 forth the manner in which the whip socket may be directed to one side or the other according to the animal desired to be urged but additional means is provided for actuating the whip socket proper to snap the whip carried therein. To this end a strong coil spring 23 is provided, one end of which is connected with the heel or rear end portion of the lever 15 while the opposite end is engaged with a loop or eye on the casting 45 8. This coil spring normally retains the lever in a predetermined position which position supports the whip upright on the device. An additional flexible connection 25 is engaged with the outer end portion of 50 the lever 15 and is directed downwardly to be guided through the aforesaid loop or eye 24. This connection extends rearwardly from the loop or eye and is engaged, in any desired manner, with the upper end portion 55 of the tilting lever 5, where the same may be readily engaged by the driver. It will thus be seen that after the whip socket has 60 been directed to the right or left by the ac-

tuation of the lever 21 the whip in the socket may be snapped to urge onward the particular animal which is lagging, by drawing upon the flexible connection 25. Upon release of engagement of this flexible connection, the whip socket carrying the whip will be returned to its initial and upright 70 position through the medium of the coil spring 23. It will be seen that the complete device may be quickly and readily operated at the will of the driver by a mere actuation of the lever 21 and the flexible connection 25, which are disposed immediately adjacent the driver's seat.

From the foregoing description of the construction of my device the manner of applying the same to use and the operation 80 thereof will be readily understood and it will be seen that I have provided an improved whip socket and manipulating means therefor which is simple and durable in construction, inexpensive to manufacture, and 85 one which will be very efficient and useful in operation.

Having thus described my invention, what I claim is:

1. In a device of the class described, the 90 combination with a supporting rod mounted for oscillation on a vertical axis, said rod being distorted intermediate of its ends and bent laterally at its upper end; of a member mounted for oscillation vertically on the upper bent end of said rod and supporting a whip socket thereon, yielding means for normally retaining said oscillating member in a predetermined position with respect to the supporting rod, means for oscillating said 100 supporting rod, and additional means for actuating the oscillating member on said rod.

2. In a device of the class described, the 105 combination with a supporting rod mounted for oscillation on a vertical axis, a segmental grooved pulley mounted on the rod adjacent the lower end thereof, flexible connections engaged at their ends with said segmental pulley and trained through the grooves of 110 the periphery thereof, and means in connection with said flexible connections for manually actuating the same and oscillating the supporting rod on its axis; of an oscillating whip support mounted on the upper end 115 of said rod, and means for actuating said support.

3. The combination with a member 120 mounted for oscillation upon a vertical axis, a second member mounted on the first named member for oscillation on a horizontal axis, a whip socket carried by the second member, and a spring for returning said second member to normal position, of a pulley secured to the first named member and designed to oscillate the same, a pair of cables 125

leading rearwardly from said pulley, a third cable leading rearwardly from the second named member, an upright lever fulcrumed at its lower end and connected to said third cable, and a second lever fulcrumed between its ends to the first named lever, said second lever being connected with said pair of cables.

In testimony whereof I have hereunto set my hand in presence of two subscribing witnesses.

JOHN T. WALSH.
